[57] CLAIM

The ornamental design for a supine sling for quadriplegics, as shown and described.

DESCRIPTION

FIG. 1 is a left side elevational view of a supine sling for quadriplegics showing my new design;

FIG. 2 is a right side elevational view thereof;

FIG. 3 is a top view thereof;

FIG. 4 is a bottom plan view thereof;

FIG. 5 is a front elevational view thereof;

FIG. 6 is a rear elevational view thereof.

The broken lines showing of the pulleys and ropes is for illustrative purposes only and forms no part of the claimed design.

The cross-hatching which indicates conventional fabric, which is partially shown in the drawing views for ease of illustration, is understood to cover the top and bottom surfaces of the support member as indicated.
